REINFORCED CONCRETE RAILWAY SLEEPER

Sverre Alfred Mork, Trondheim, Norway

Application December 15, 1949, Serial No. 133,155

1 Claim. (Cl. 238—84)

1

This invention relates to a railway sleeper made of reinforced concrete, preferably with an asphalt covering when necessary against alkaline water and poisonous soil. It consists of three concrete parts. The third part, which is of cylindrical or the like form, is arranged between the two other parts and together with pads fill up the space between these. The two parts of the sleeper on both sides of said third part are resiliently secured together by members holding a hard-rubber washer.

The invention also provides for improvements as to the fastening of the rails to the sleeper. These improvements also include arrangements in order to reduce the effect of wheel shocks against the rail joints, particularly in curves, and thereby reduce the stress on the resilient connecting means of the sleeper parts.

The type of concrete sleepers previously made in two parts is now improved by the three parts system, that gives a double adjusting possibility for widening of the track width at curves.

The essential features of the present invention are as follows:

Each of the two end parts of the sleeper consists of reinforced concrete and are on the transversal sides, which face each other, formed in such a way that they embrace a third part of the sleeper, which part has a cylindrical or the like form and is made of concrete. Between the two outer parts of the sleeper, and between each of them and the cylindrical part, are provided pads of perforated sheet metal formed like rasps and with asphalt paper or other suitable material pressed down and against both sides of the perforated metal plates. The connecting arrangement between the two end parts of the sleeper comprises longitudinal bolts, which are joined to each other in pairs by means of transverse bolts. The shanks of the top pair of longitudinal bolts may be looped preferably substantially at the middle, while the shanks of the lower pair of bolts are preferably straight.

According to a feature of the invention transversal eyebolts are screwed into threaded pipes, which pipes are oiled on their inside and are cast into the end parts of the sleeper. Between the iron washers and the nuts of the longitudinal connecting bolts and the transverse eyebolts are provided washers of hard-rubber or the like to give flexibility.

The fastening of the rails to the sleeper is effected by means of anchoring bolts whose heads grip across the rails, each bolt being held in a branched socket cast into the sleeper, and hav-

2

ing at the end of the bolt a projecting toe which projects under a shoulder of the branch of the socket, preferably under a piece of hard steel welded to said shoulder and secured there by a lock bolt placed at the back side of the anchoring bolt in the socket. The heads of the bolt grip across the tie plate.

The bolts are interlocked by a cover clinched over their heads, tying them together.

The socket is to be filled with pitch oil which lubricates and prevents formation of rust as well as wear and tear, and makes it easy to replace the bolts.

The bolts for fastening the rails to the sleeper have arrangements to counteract the pressure sideways. For this purpose the head of the anchoring bolt on the outer side of the rail is provided with an upward extension which serves as a bearing for a shaft carrying a wheel of hard rubber which thrusts against the web of the rail.

In order to prevent sleepers from sliding along the rails on steep gradients, the anchoring bolts are provided with a set screw and a lock nut, that when tightened hold the sleepers in place relatively to the rails. Between the tieplate and the concrete sleeper is placed a plate which is perforated and formed like a rasp on both sides, on which sides are pressed asphalt paper or the like material.

Each of the outer parts is provided with reinforcing members for prestressing the concrete.

The above described railway sleeper has essential advantages:

Owing to the third cylindrical concrete part between the outer parts of the sleeper, adjustment of the distance between the rails in curves can easily be performed by dividing the difference in rail gauge by one half on each of the outer parts of the sleepers. The spaces between each of the outer parts and the cylindrical part of the sleeper are filled with pads, as mentioned above.

The parts of concrete sleeper will be held in proper place. The stresses on the connecting bolts and sleeper parts are likewise reduced by the flexible arrangement of the hard-rubber washers and the hard-rubber wheel against the rails.

By making the sleeper in the way described the production may be simplified, as each of the outer parts of the sleeper are alike, an advantage not obtained when the parts are made with key and slot. As the transverse eyebolts are screwed into oil pipes and because of the washers of hard-rubber between the nuts of the longitudinal bolts and the transversal eyebolts, easy replacement of

worn parts may take place. This has not been achieved in constructions known up to this time. The washers of rubber increase moreover the resiliency between the parts and the rail.

The drawing shows as an example one embodiment of the reinforced concrete sleeper.

Fig. 1 is an elevation, partly in section, showing the connection between the parts of the sleeper and the arrangement for the fixing of the rails to the sleeper.

Fig. 2 is a plan view of the same.

Fig. 3 shows details of the three main parts of the sleeper, with the pads and the pipes, that are moulded into the end parts of the sleeper.

Fig. 4 shows in perspective said pads and the cylindrical part of the sleeper, which is to be embraced by the pads.

Fig. 5 shows in detail the transverse members consisting of the pipes with inside threads, to be cast into the end parts of the sleeper, and the eyebolts to be screwed into the pipes.

Fig. 6 is an enlarged sectional view of the anchorage bolts and the rail with the rail tie-plate. The figure also shows the arrangement to counteract the pressure sideways of the train.

Fig. 7 shows in detail a plan view of the pad used between the sleeper and the rail tie-plate and which consists of a plate of sheet metal, perforated and formed like a rasp, against the sides of which is pressed asphalt paper or similar material.

Fig. 8 is a detail view of the hard rubber washer.

The reference letters *a* and *b* indicate the two outer or end concrete parts of the sleeper and *c* the cylindrical concrete part, which is placed between the parts *a* and *b*. Between *a* and *b* respectively and between each of these parts and part *c* are provided pads, each consisting of plates *d*₁ and *e*₁, see Fig. 4, part of which has a half cylindrical profile to fit into half cylindrical recesses in the parts *a* and *b* and to embrace part *c*. The plates *d*₁ and *e*₁ are perforated and serrated around the holes, so that both sides of the plates become similar to a rasp. Asphalt paper or other suitable material *d*₂ and *e*₂ respectively is pressed against each side of the plates.

The longitudinal bolts which interconnect the outer or end parts of the sleeper consist of the numbers *f*₁ and *f*₂, which in their middle part are looped, and of the numbers *g*₁ and *g*₂ which are straight. The bolts *f*₁ and *f*₂ interconnect the sleeper parts *a* and *b* by means of the eyebolts *h*₁ and *h*₂, each of which is screwed into a transverse and threaded pipe *k*, moulded into part *a*, and further by means of the eyebolts *j*₁ and *j*₂, each screwed into another pipe *k*, moulded into sleeper part *b*. The pipes *k* are filled with pitch oil and handy replacements of the eyebolts, if desired. Nuts *l* hold the longitudinal bolts to the transverse eyebolts.

Between each of the eyebolts *j*₁ and *j*₂ and the nut *l* on the respecting longitudinal bolt is a washer *m* made of hard-rubber, and also a steel washer *n*. The bolts *g*₁ and *g*₂ connect the parts *a* and *b* by means of the eyebolts *o*₁ and *o*₂ and *p*₁ and *p*₂ screwed into pipes *k*. Each of the eyelets *o*₁ and *o*₂ is provided with a square hole which is engaged by a square portion at the end of the respecting tie bolts *g*₁ and *g*₂, each of which is provided with a head *q* placed against the outside of the eyebolts. Each of the bolts *g*₁ and *g*₂ is threaded on the opposite end and carries attaching nuts *l* for securing to the eyebolts *p*₁ and *p*₂. As for the upper pair of bolts, a rubber

washer *m* and a steel washer *n* are placed in between each of the eyebolts *p*₁ and *p*₂ and nut *l* on the longitudinal bolt *g*₁ and *g*₂ respectively.

Between each of the rails *v* and the sleeper are placed an ordinary tie plate *w* and a pad *a*₁, which pad, as above mentioned, consists of a perforated and raspformed sheet metal plate with asphalt paper pressed against both sides. The anchoring of the rails to the sleeper is such that vertical branching sockets are moulded into the sleeper and arranged for receiving a projection or bending of the bolt *r* or *x* respectively, which bolts connect the rails with the sleeper. Each of the sockets also receives a lock bolt *i* connected with the anchoring bolt by means of a cover *a*₂, which is pressed down upon the heads of the anchoring bolt and the lockbolt, thus securing the bolts.

To counteract the sideways pressure on the rail from the train, the outer anchor bolt *r* (see Fig. 6) is provided with an arm *s* which carries a bearing for a shaft *t*, carrying a wheel *u* of hard-rubber or similar material, which the wheel thrusts against the web of the rail *v*. In order to hold 20 the sleeper and the rail together with a tight grip, the anchoring bolts through the head are provided with a set screw *y* and a lock nut, which will press the toe *x* of the anchoring bolt against the steel plate *z* of the socket *ae*.

Letter *ö* indicates the reinforcing members, used to obtain the pre-stressed concrete structure.

I claim:

A rail anchoring device for securing a rail to a tie having a vertical bore therein formed with a laterally enlarged lower portion defining a downwardly facing inclined shoulder; said anchoring device comprising an anchoring bolt having a head extending laterally from one end for overlying the base flange of a rail on the 35 tie and a laterally extending inclined toe projection on the other end formed to extend loosely through the vertical bore and to underlie the inclined shoulder in parallel relationship to the latter, a locking bolt having a shank dimensioned for extending into the vertical bore alongside said anchoring bolt and to fill the bore for preventing lateral movement of said anchoring bolt in the bore, a clamping bolt extending threadedly down through said head of the anchoring bolt for bearing at its lower end against the base flange of the secured rail to thereby urge said inclined toe projection into bearing engagement with the downwardly facing inclined shoulder so that the bearing engagement of the inclined toe projection 40 and shoulder causes the anchoring bolt to bear laterally against said locking bolt and prevent removal of the latter from the bore, an arm projecting upwardly from said head of the anchoring bolt, and a roller member mounted on the upper end of said arm for engagement against the web of the secured rail to resist outward lateral movement of the latter.
